UNITED STATES PATENT OFFICE.

ERIC SJODEN, OF BUFFALO, NEW YORK, ASSIGNOR TO AMERICAN RADIATOR COMPANY, A CORPORATION OF NEW JERSEY.

DESIGN FOR A RADIATOR.

No. 38,516.

Specification for Design.

Patented April 9, 1907.

Application filed March 9, 1907. Serial No. 361,628. Term of patent 14 years.

To all whom it may concern:

Be it known that I, ERIC SJODEN, a citizen of the United States, and a resident of Buffalo, county of Erie, and State of New York, have invented a new, original, and ornamental Design for Radiators, of which the following is a specification, reference being had to the accompanying drawing, forming part thereof.

The figure is a front elevation of a radiator, showing my new design.

I claim—

The ornamental design for a radiator, as shown.

ERIC SJODEN.
